(57) **CLAIM**

The ornamental design for a tubing component for a game, as shown and described.

DESCRIPTION

FIG. 1 is a perspective view of a tubing component for a game showing our new design;

FIG. 2 is a front elevation view thereof; the rear view being a mirror image;

FIG. 3 is a left-side elevation view thereof;

FIG. 4 is a right-side elevation view thereof; and,

FIG. 5 is a perspective view thereof; showing the tubing component for a game in its environmental of use.

The dot-dash broken line illustrates the bound of the claim that form no part the claimed design. The remaining broken lines depict environmental structure of the tubing component for a game that form no part of the claim.

1 Claim, 5 Drawing Sheets
